CLAIM

The ornamental design for a display device, as shown and described.

DESCRIPTION

FIG. 1 is a front perspective view of a display device showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the figures illustrate portions of the display device that form no part of the claimed design. The oblique shade lines in the figures show a transparent, reflective, or shiny surface, and not surface ornamentation.
